UNITED STATES PATENT OFFICE.

RAYMOND D. ANGSTEAD, OF FAIRFIELD, IOWA, ASSIGNOR OF ONE-HALF TO WILLIAM H. ANGSTEAD, OF FAIRFIELD, IOWA.

BAG-HOLDER.

1,159,152.

Specification of Letters Patent.

Patented Nov. 2, 1915.

Application filed March 25, 1915. Serial No. 16,893.

To all whom it may concern:

Be it known that I, RAYMOND D. ANGSTEAD, a citizen of the United States, residing at Fairfield, in the county of Jefferson and State of Iowa, have invented certain new and useful Improvements in Bag-Holders; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in bag holders and consists of a simple and efficient device of this nature having various details of construction, combinations and arrangements of parts which will be hereinafter fully described, shown in the accompanying drawings and then specifically defined in the appended claims.

My invention is illustrated in the accompanying drawings, in which:

Figure 1 is a perspective view showing the device set up for use and the bag applied thereto. Fig. 2 is a vertical sectional view through the bag engaging bands, and Fig. 3 is a transverse section.

Reference now being had to the details of the drawings by letter, A, A designate two legs which cross each other and which have at their points of intersection apertures for the reception of a bolt B upon which a nut C is mounted, forming means for holding the two legs together and crossed as shown. A bar, designated by letter D, is fastened at its ends to the two legs and affords a further means for holding the same rigidly in the position shown. A third leg, design-

nated by letter E, is connected to one of the other legs by means of a semi-circular band F, and H is a brace connecting the band with the leg E, thus securely holding the latter in a fixed position.

The upper ends of the several legs are provided with holes K and are adapted to receive the hooked ends of the arms O which are fastened to the inner band N over which the upper end of the bag is adapted to be folded, as shown in the drawings. A clamping band, designated by letter R, has ends which are apertured for the reception of the screw T upon which a nut S is mounted, said band being adapted to fit over the band as shown when adjusted in place and, by tightening the nut upon the screw, the bag may be securely held in place.

After the hooked ends of the arms are inserted in the holes in the ends of the legs, they will form suitable supports for the bag. The concaved band, while securely holding the legs, will be out of the way of the lower portion of the bag when filled.

What I claim to be new is:—

A support for bag holders comprising two inclined legs which cross together and are secured at their point of intersection, a third leg, vertically disposed and spaced apart from the other legs, a bar secured to the inclined leg below its pivotal connection and secured to the vertical leg, a brace secured at one end to the bar and the other end to the vertical leg.

In testimony whereof I hereunto affix my signature in presence of two witnesses.

RAYMOND D. ANGSTEAD.

Witnesses:

ANTON R. CARLSON,
W. H. ANGSTEAD.
